CLOTHES HANGER

Bruce Burns, Yucca Valley, Calif.

Application April 8, 1948, Serial No. 19,797

4 Claims. (Cl. 223—94)

1

This invention relates to improvements in clothes hangers and more particularly to a clothes hanger having extendible arms which can be folded to permit the hanger to be slipped through the neck of a garment or readily packed for traveling.

Many garments, such as shirts, blouses and children's dresses, when hung upon clothes hangers of conventional type must have the neck opening unbuttoned to permit the insertion of the hanger into the body of the garment. But, after the garment has been hung up the opening has to be buttoned again to insure that it will not wrinkle and that it will not slip off the hanger.

This problem is particularly vexatious in the manufacture of dresses and blouses with small neck openings. When these garments are pressed in the factory, the opening is closed. However, to permit the hanging of the garments while they are awaiting shipment, the opening must be unbuttoned and buttoned again. When the garments are removed from conventional hangers for shipping, the same process must be run through all over again. Finally, when the clothes are unpacked in the store the opening must once again be unbuttoned and buttoned when the garment is hung up for display.

Not only does this buttoning and unbuttoning of the clothes consume, in the aggregate, a great amount of time, but, due to excessive handling, it is not long before the neck opening of garment becomes crumpled or soiled and the value and salability of the merchandise reduced. In addition, there is always a possibility that a packer or sales person will attempt to remove a garment from the hanger without opening the neck, thus tearing the garment and reducing its value. Of course, similar problems arise in the home and there is a real need for a hanger which can be inserted in the body of the garment without opening the neck.

It is a primary object of my invention to provide a clothes hanger which has extendible arms which can be folded to permit the insertion of the hanger into the body of a garment without opening the neck closure.

Another object of my invention is the provision of a clothes hanger which has extendible arms which can be folded through the medium of retraction means connected to the arms.

A further object of my invention is the provision of a clothes hanger having extendible arms which have embodied thereupon suspensory elements adapted to support skirts or similar garments.

2

Another object of my invention is the provision of a clothes hanger having extendible arms which is light in weight, has few working parts and can be easily and cheaply manufactured.

Other objects and advantages of my invention will appear from the following specification and the drawing, which are for the purpose of illustration only and in which:

Fig. 1 is a vertical elevational view showing a hanger constructed in accordance with my invention with the arms extended;

Fig. 2 is a vertical, partially sectional view taken on broken line 2—2 of Fig. 1;

Fig. 3 is a vertical elevational view showing the hanger with its arms folded;

Fig. 4 is a perspective view showing the manner in which the hanger arms can be folded with one hand;

Fig. 5 is an enlarged, fragmentary, sectional view taken on line 5—5 of Fig. 1 and showing the means used to suspend its arms from the hanger;

Fig. 6 is an enlarged, fragmentary, sectional view taken on broken line 6—6 of Fig. 1; and

Fig. 7 is an enlarged detail view which shows the manner of securing the extension element to the arms.

Referring to Figs. 1 to 7, I show a clothes hanger 10 having a yoke member 12 and a pair of garment supporting arm members 13 pivotally supported on said yoke member. The hanger 10 is shown as manufactured from a plastic material but I do not intend to limit my invention to any particular material since it could conceivably be fashioned with equal facility out of wood or metal.

The yoke member 12 of the hanger 10 is of generally arcuate conformation to conform to the shoulder line of the suspended garment and consists of a front molding 14 and a back molding 15. The front molding 14 and the back molding 15 may be cemented or otherwise permanently joined together and a pilot boss 16 is formed on the interior of the front molding 14 which fits into a pilot hole 17 on the back molding 15 to permit the accurate registry of the moldings while they are assembled.

Formed integrally on the top of the yoke member 12 is an annular, flanged gripping portion 19 which is crowned by a cylindrical boss 21. The cylindrical boss 21 is capped by a ferrule 22 which is adapted to assist in securing the front and back moldings of the yoke 12 together. A vertical hole 23 is formed in the center of the yoke which registers with a hole 24 formed in the center of the ferrule 22. Revolubly mounted in the hole 23 is a cylindrical stud member or suspension

member 25 which has an enlarged foot portion 26 secured within a cavity 27 formed in the interior of the yoke 12 at the base of the hole 23 in such a manner as to prevent the dislodgment of the stud member 25 from the hole 23.

The upper end of the stud member 25 has a cylindrical knob 28 formed integrally therewith which has a transverse hole 29 in it adapted to receive the lower end 31 of a hook member 32 from which the hanger 10 is intended to be suspended. The hook member 32 is revolvable in the hole 29 and can thus be folded downwards, as best shown by the dotted lines in Fig. 2, to permit the use of the hanger 10 for traveling purposes. The annular, flanged gripping portion 19 of the yoke 12 is designed to permit the hanger 10 to be suspended between two fingers of one hand while the arms 13 of the hanger are being folded, as shown in Fig. 4.

As indicated above, the garment supporting arms 13 of the hanger 10 are pivotally mounted upon the yoke 12. The pivot means 33, as best shown in Fig. 5, upon which the arms 13 are suspended is formed integrally with the yoke 12 and consists of an instruck, circular male member 34 formed in the back molding 15 which is adapted to project through a hole 35 formed in the inner end of the arm 13 and be seated in a flanged orifice 36 integrally formed in the front molding 14. Therefore, the arms 13 are secured to the yoke 12 at the time that the front and back moldings are joined together and there is no need for the utilization of auxiliary screws or pins to retain the arms 13 in the yoke 12.

The arms 13 are of identical conformation and are so shaped as to adequately receive and support a garment which is hung thereupon. As shown in Fig. 6, the arms 13 are generally of I or T cross section over the greater portion of their length and have stop portions 37 integrally formed in their inner ends which are adapted to impinge on stop portions 38 formed on the underside of the yoke 12 and thus effectively prevent the arms 13 from being folded or extended beyond definite, predetermined limits.

Disposed upon the inner ends of the arm members 13 and positioned opposite each other are integrally formed frusto-conical bosses 39 which are adapted to act as securing means for the ends of an extension element 41 which, in the embodiment of the invention under consideration, consists of a close wound helical spring 42 having its opposite ends 43 pressed, screwed or otherwise adequately secured to the bosses 39. I do not intend to limit my invention to the utilization of a close wound helical spring as an extension element since it is conceivable that other expedients, such as hour glass wound or barrel shape wound springs, having the same function might be readily substituted therefor.

As clearly shown in Fig. 7, each end 43 of the spring 42 is considerably expanded upon one of the bosses 39 and serves to partially obstruct an opening 44 onto a track 45 which is created upon the lower flange of each arm 13. Mounted upon each track 45 and adapted to be moved thereupon is a suspensory element 46 which has a groove 47 cut in its top which is adapted to secure the suspensory element 46 upon the track. The suspensory elements are of substantially hook-shaped configuration and are adapted to support a skirt or similar garment. The suspensory elements 46 are installed upon the tracks 45 by being inserted through the openings 44. This installation takes place before the extension ele-

ment 41 is mounted upon the bosses 39. Once the suspensory elements 46 are installed upon the tracks 45 and the extension element 41 mounted upon the bosses 39, the suspensory elements 46 cannot be inadvertently dropped or otherwise removed from the tracks 45. They are kept upon the tracks 45 because the openings 44 to the tracks 45 are partially blocked by the enlarged ends 43 of the spring 42. Thus, the spring 42 serves not only to keep the arms 13 extended but also to retain the suspensory elements 46 upon the track 45.

When the spring 42 is positioned between the inner ends of the arms 13 in its normally straight state, it keeps the arms 13 extended outwardly from the yoke 12. Even a heavy load imposed on the outer ends of the arms 13 will not overcome the columnar effect supplied by the spring 42. However, as most clearly shown in Fig. 4, when the hanger 10 is supported between two fingers of one hand and the thumb of the same hand is placed below the spring 42, a light upward movement of the thumb will cause upward deflection of the spring 42 and pull the arms 13 in and down until they assume the position shown in Fig. 3. The hanger 10 is then susceptible of being removed from or inserted in the closed neck of a garment.

Formed integrally with the extreme outer ends 30 of the arms 13 are oppositely disposed hook elements 49 which, when engaged one within the other in cooperative relationship, as shown in Fig. 3, prevent the movement of the arms 13 into the extended position. The engagement of the 35 hook elements 49 is achieved by slightly deflecting one arm laterally as the ends of the arms are brought together. The expansive force of the spring 42 tends to urge the arms 13 apart but in so doing also engages the hook elements 49 more 40 securely with each other. By providing the hook elements 49 to secure the ends of the arms together and the revolvable hook element 32, I adapt the hanger for use as a traveling hanger which can be easily and readily packed away.

45 My invention provides a clothes hanger having garment supporting arms which can be readily folded with one hand which will, when extended, assume a garment supporting position. Also provided in the hanger are suspensory elements 50 which are retained upon the hanger by means of the extension element which keeps the arms in the extended position. The hanger consists of a small number of parts, can be easily assembled and manufactured and can be a moderately 55 priced article.

Although I have shown and described preferred embodiments of my invention, it will be appreciated that other elements may be substituted for the elements shown herein, and I, therefore, do 60 not intend to be limited to the specific construction shown but desire to be afforded the full scope of the following claims.

I claim as my invention:

65 1. A clothes hanger adapted, when in its open position, to support a garment, the parts of which are adapted to be moved from said open position into a closed position in which they can be readily inserted into a garment through the neck opening thereof without unbuttoning the garment, comprising: a central yoke; a suspension member secured in the upper central portion of said yoke and extending upwardly therefrom, the upper portion of said suspension member being so shaped as to be readily engaged by 70 a hook or other supporting member; two gar- 75

ment supporting arms, one of these garment supporting arms being pivoted at one end to one side of said yoke and the other of these garment supporting arms being pivoted at one end to the other side of said yoke, said yoke being narrower in width than the neck of a garment which the hanger is designed to support, the upper edges of said arms when said hanger is in its open position being so curved as to conform to the shoulder lines of said garment; and a helical spring, one end of said spring engaging one of said arms and the other end of said spring engaging the other of said arms, said spring being so placed and of such length that when said arms are in their extended position the spring extends in a straight line between said arms and acts as a column or strut which resists any tendency of said arms to move away from said extended position.

2. A clothes hanger adapted, when in its extended position, to support a garment by extending outwardly at either side of a yoke and inside said garment, the parts of which are adapted to be moved to a closed position in which they can be inserted into a garment through the neck opening thereof without unbuttoning the garment, comprising: a central yoke; two legs formed in said yoke straddling a central space in the center of said yoke; a suspension member engaging said yoke and adapted to be engaged by a hook or other supporting means; two garment supporting arms, one of these garment supporting arms being pivoted on one of said legs of said yoke and the other of said garment supporting arms being pivoted on the other leg of said yoke, said yoke being narrower in width than the neck space of the garment which it is intended to support, and said garment supporting arms when in their closed position being readily inserted into the garment through the neck space of said garment without unbuttoning the garment, the upper edges of said garment supporting arms, when said hanger is in its open position, being curved to conform to the shoulder lines of said garment; and a helical spring one end of which is secured to and abuts against one of said garment supporting arms and the other end of which abuts against and is secured to the other of said garment supporting arms, said spring being of such length and so placed that when said garment supporting arms are in their open position said spring extends in a straight line between said garment supporting arms and acts as a column or strut resisting any tendency of said garment supporting arms to move out of their open position, said spring being so positioned that when said spring is flexed to allow said garment supporting arms to move into their closed position the central portion of said spring is forced into the space between the legs of said yoke.

3. A clothes hanger adapted, when in its open position, to support a garment, the parts of which are adapted to be moved from said open position into a closed position in which they can be readily inserted into a garment through the neck opening thereof without unbuttoning the garment, comprising: a central yoke; a suspension member secured in the upper central portion of said yoke and extending upwardly therefrom, the upper portion of said suspension member being so shaped as to be readily engaged by a hook

or other supporting member; two garment supporting arms, one of these garment supporting arms being pivoted at one end to one side of said yoke and the other of these garment supporting arms being pivoted at one end to the other side of said yoke, said yoke being narrower in width than the neck of a garment which the hanger is designed to support, the upper edges of said arms when said hanger is in its open position being so curved as to conform to the shoulder lines of said garment; and a spring, one end of said spring engaging one of said arms and the other end of said spring engaging the other of said arms, said spring being so placed and of such length that when said arms are in their extended position the spring extends in a straight line between said arms and acts as a column or strut which resists any tendency of said arms to move away from said extended position.

4. A clothes hanger adapted, when in its extended position, to support a garment by extending outwardly at either side of a yoke and inside said garment, the parts of which are adapted to be moved to a closed position in which they can be inserted into a garment through the neck opening thereof without unbuttoning the garment, comprising: a yoke; a centrally located receptacle formed in said yoke; two garment supporting arms, one of said garment supporting arms being pivoted at one side of said yoke adjacent said receptacle and the other of said garment supporting arms being pivoted at the other side of said yoke adjacent said receptacle, said yoke being narrower in width than the neck space of the garment which it is intended to support, and said garment supporting arms when in their closed position being readily inserted into the garment through the neck space of said garment without unbuttoning the garment, the upper edges of said garment supporting arms, when said hanger is in its open position, being curved to conform to the shoulder lines of said garment; and a spring one end of which is secured to and abuts against one of said garment supporting arms and the other end of which abuts against and is secured to the other of said garment supporting arms, said spring being of such length and so placed that when said garment supporting arms are in their open position said spring extends in a straight line between said garment supporting arms and acts as a column or strut resisting any tendency of said garment supporting arms to move out of their open position, said spring being so positioned that when said spring is flexed to allow said garment supporting arms to move into their closed position the central portion of said spring is forced into the receptacle in said yoke.
